TRAVELING VALVE

Frank L. Maire, Lima, Ohio

Application February 16, 1935, Serial No. 6,795

3 Claims. (Cl. 103—225)

This invention relates to liquid pumping valves and more particularly to traveling valves of the multi-cup type used in the usual barrel for pumping oil or water.

Heretofore known valves of the above design have been unsatisfactory for the reason that, in operation, the top cup usually did all of the work while the lower ones remained idle and dried out. This condition, though general, was particularly true when the supply of liquid being pumped became exhausted, leaving merely a column of liquid in the barrel and tubing above the valve. As the result of this faulty operation, the dry cups below the top one soon burned out. Obviously, the seal provided by a single cup was poor and the liquid being pumped escaped around the single cup in operation, reducing the efficiency of the valve. Furthermore, when oil was being pumped, its escape past the cup caused it to become more or less emulsified with water present, or what is known as roiley. The roiley oil in the output from the well lowered its quality and consequently its value.

The cause for the above indicated trouble resides in the fact that the cups below the top one are not properly lubricated, and have nothing to force them against the wall of the barrel in which they work. Attempts have been made to overcome the lack of lubrication in the lower cups of traveling valves by admitting oil behind them from the hollow center of the valve body. This method, however, has been a failure for the reason that valves designed for this operation are not only too complicated to be commercially practical, but also are necessarily of such design that they become inoperative by reason of sand and foreign particles choking the internal passages.

An object of the invention is, therefore, to overcome the above difficulties by providing passage ways on the exterior of the standard traveling valve body to conduct a portion of the liquid pumped in the barrel and the tubing above the valve cups, to the space behind all of the valve cups to lubricate them and to force them into tight engagement with the barrel wall.

Another object of the invention is to provide a traveling valve having self lubricating cups.

These and other objects will be apparent from the following specification when taken with the accompanying drawing in which

Fig. 1 is a sided elevation of the improved traveling valve partially in section to show details of the construction,

Fig. 2 is an enlarged section on the line II—II of Fig. 1, and

Fig. 3 is a vertical section through one of the valve rings.

Referring to the drawing, the reference character 1 indicates a barrel of the usual type joined to the bottom of a well tubing, in which the traveling valve is vertically reciprocated by any suitable pumping mechanism such as a jack or a beam located at the surface of the earth. The 10 traveling valve comprises a tubular body 2 having threaded to its lower end a lower cage 3 and to its upper end a ball cage 4. A ball 5 is disposed within the ball cage 4 and normally rests on a seating ring 6. A threaded projection 7 is formed 15 on the top of the ball cage 4 to which a sucker rod, not shown, passing up through the tubing connected to the barrel, is connected for providing an operative connection between the traveling valve and the pumping mechanism. Disposed on the 20 body 2 between the lower cage 3 and the ball cage 4 are slidably disposed a plurality of alternately arranged valve cups 8 and valve rings 9. A washer 10, for purposes of design, is used above the top valve cup 8, in place of a valve ring 9. 25

In operation, during downward movement of the traveling valve, the liquid pumped passes relatively upwardly through the tubular body 2 and past the ball check valve at the upper end of the body 2 comprised by the ball 5 and the seating ring 6. Upon reversal of movement of the body 2 to an upward direction, the ball 5 seats on the seating ring 6 preventing the escape of 30 liquid through the center of the body 2. The function of the cups is to prevent the escape of 35 liquid between the valve body 2 and the barrel 1 from the barrel 1 and tubing above the traveling valve. The structure thus far broadly described comprises the traveling valve in general use to-day, but it is unsatisfactory for reasons above 40 stated, as only the upper cup 8 acts to prevent the escape of liquid between the body 2 and the barrel 1.

According to this invention, the body 2 is provided with a plurality of axially extending grooves 45 15 in its outside surface. Also the valve rings 9 are provided with a plurality of radially extending bores 16 and internal annular grooves 17 communicating with the bores 16. The axially extending grooves 15, the annular grooves 17, and the radially extending bores 16 form a plurality of passages from the space in the barrel 1 and the tubing, above the valve cups 8, to the 50 space behind each cup 8. The passages thus 55

formed conduct liquid from above the cups 8 to the spaces behind the cups 8.

This liquid is under a pressure equal to the weight of liquid in the tubing above the barrel 5 and consequently is great enough to force the cups 8 tightly against the barrel 4 and to keep them constantly lubricated. This liquid also serves as a cushion reinforcing and strengthening the cups, thereby increasing their life and efficiency. The result is that they do not dry or 10 burn out and as all the cups work together, the efficiency of the valve is greatly increased that is the valve operates for a period very much greater than the period for which a valve will 15 operate when the axial grooves and passageways are not provided.

It should be noted that the size of the axial grooves and passageways conducting liquid to behind the cups 8 should be restricted, as for 20 instance as shown, so that by their size and the tortuous course defined thereby there results a lesser pressure at the last cup than at the top cup, and the tendency of liquid to leak past the last cup is reduced. The tendency to leak past 25 the last cup is less than the tendency to leak past the first cup also for the reason that the last cup is not subject to the direct impulse or shock due to the inertia of the head of liquid above the entire valve when the valve changes from 30 traveling downwardly to traveling upwardly, as is the top cup. Should it be found desirable, the size of the axial grooves and passageways may be graduated, the size of those at the bottom of 35 the valve being smaller than those at the top to bring about the proper distribution of liquid.

While the foregoing specification discloses a plurality of axially extending grooves in the surface of the body 2, it is contemplated that a single axially extending straight or spiral groove may 40 be used. Furthermore, the liquid conducting passages may be appropriately disposed in valve cups alone or in the valve cups and valve rings, if desired rather than as shown. I therefore do not wish to be limited except by the scope of the 45 following claims.

I claim:

1. A traveling valve for use in a barrel for pumping liquid comprising a body, an inner bore defined thereby through which liquid pumped 50 passes, a plurality of valve cups disposed on said body for providing a liquid tight seal between

said body and the barrel in which it works, valve rings disposed on said body spacing said cups, an axially extending groove in the surface of said body providing a communication along said body with the space in the barrel above said cups, internal annular grooves in said rings in communication with said axially extending groove, and ports in said rings providing communication between said cups and said annular grooves, whereby a portion of the liquid pumped into the barrel 10 above said cups passes through said groove, annular groove and ports to said cups to lubricate the same and to force them outwardly against the barrel wall.

2. A traveling valve for use in a barrel for 15 pumping liquid comprising a body, an inner bore defined thereby through which liquid pumped passes, a check valve at the upper end of said body for checking downward flow of liquid through said bore, a plurality of valve cups disposed on said body below said check valve for providing a liquid tight seal between said body and the barrel in which it works, chamber defined by said body, the barrel and adjacent valve 20 cups, and means comprising a superficial groove 25 in said body for conducting a portion of the liquid pumped from above said cups to said cups and said chambers for lubricating said cups and the barrel wall and for forcing said cups against the barrel wall.

3. A traveling valve for use in a barrel for pumping liquid comprising a body, an inner bore defined thereby through which liquid pumped passes, a plurality of regularly functioning valve 30 cups disposed on said body for providing a liquid tight seal between said body and barrel in which it works, valve rings disposed on said body spacing said cups, adjacent cups defining, with the spacing ring therebetween, chambers each having a side thereof defined by said barrel, an axially 35 extending groove in the surface of said body providing a communication along said body with the space in the barrel above said cups, and passages in said valve rings providing a communication between said groove and said chambers for conducting a portion of the liquid pumped into the barrel above said cups to said cups and chambers to lubricate the cups and the barrel wall and to force the cups outwardly against the barrel wall.

CERTIFICATE OF CORRECTION.

July 28, 1936.

Patent No. 2,049,166.

FRANK L. MAIRE.

It is hereby certified that error appears in the printed specification of the above numbered patent requiring correction as follows: Page 1, second column, line 16, for "page" read cage; and page 2, second column, line 23, claim 2, for "chamber" read chambers; and that the said Letters Patent should be read with these corrections therein that the same may conform to the record of the case in the Patent Office.

Signed and sealed this 22nd day of September, A. D. 1936.

Henry Van Arsdale
Acting Commissioner of Patents.
